EMERGENCY WARNING LAMP

Robert D. Kahn, Rockville Centre, N.Y., assignor to
Fedtro, Inc., Rockville Centre, N.Y., a corporation of
New York

Filed May 23, 1967, Ser. No. 7,234

Term of patent 14 years

(Cl. D72—1)

FIG. 1

FIG. 2

FIG. 3

FIG. 4

FIG. 5

FIG. 1 is a front elevational view of the emergency warning lamp and showing the rotating beam unit through the transparent cap;

FIG. 2 is a side elevational view of the warning lamp and showing the plug in dot and dash lines;

FIG. 3 is a top plan view of the warning lamp, the bottom plan view being plain;

FIG. 4 is a rear elevational view of the warning lamp; and

FIG. 5 is a top perspective view of the warning lamp and illustrating a second embodiment having a switch on the side of the housing.

The dominant features of the design reside in the portions shown in full lines.

I claim:

The ornamental design for an emergency warning lamp, as shown and described.
